JOHN E. KALGREN, OF MINNEAPOLIS, MINNESOTA, ASSIGNOR TO THE J. R. CLARK CO.,
OF MINNEAPOLIS, MINNESOTA, A CORPORATION OF MINNESOTA

IRONING TABLE

Application filed February 13, 1928. Serial No. 253,866.

My present invention provides an extremely simple and highly efficient low cost ironing table; and, generally stated, the same consists of the novel devices and combinations 5 of devices hereinafter described and defined in the claims.

The commercial form of the improved ironing table is illustrated in the accompanying drawings wherein like characters indicate like parts throughout the several views. 10

Referring to the drawings:

Fig. 1 is a side elevation of the improved ironing table;

Fig. 2 is a perspective view of the table 15 looking upward at the same; and

Fig. 3 is a section taken on the line 3—3 of Fig. 1.

The complete ironing table comprises an ironing board 4, rear legs 5 and oblique leg 20 6 and a brace arm 7. The rear legs 5 are connected by bolts or rivets 8 pivoted to the down-turned ears 9 of a metallic hinged bar or member 10 that is riveted or otherwise rigidly secured to the bottom of the rear end 25 portion of the board 4. The oblique leg 6 is a bifurcated member made up of two bars, the lower ends of which are brought together and rigidly tied together by a rivet 11 or other suitable device. The spread upper ends 30 of the bars that make up this oblique leg 6 are pivotally connected to the hinged lugs 9 by the hitherto noted pivot bolts or rivets 8, but are located on the inner sides of said lugs, whereas the lugs 5 are located on the 35 outer side of said lugs. The rear legs 5 have a downward spread and are tied together by tie slats 12 so that they move pivotally together as a complete rear leg structure.

The brace arm 7 is also a bifurcated member 40 and is made up of bars which at their spreading ends are pivotally connected to the rear legs 5 by rivets or bolts 13. The free ends of the bars that make up said brace 7 are brought quite closely together and are tied 45 together by a short tie bar 14. At the inter-

mediate portions, the bars of said brace 7 are further tied together by a transverse stop bar 15. The bars of the oblique legs 6, at their pivoted ends have beveled short end extensions 6^a that stop against the bottom of the board 4. Preferably, however, yielding abutments, such as rubber buttons 16, are interposed between the ends 6^a and the board, being, as shown, secured to the bottom of said board. The free ends of the brace bars 7 55 are beveled and have an interlocking engagement with a shoulder formed on the bottom of the board 4 by a lock cleat 17 rigidly secured to said board.

With the construction described, when the board 4 is set in an upright position on its large end and the leg structures are released they will drop into operative positions except that a slight force will be required to spring the free ends of the brace bars 7 into interlocking engagement with the lock cleat 17. 60 When the parts are set up, as shown in the drawings, the stop bar 15 on the brace 7 will engage the oblique leg 6 and force the same down as far as it will go, thereby putting the yielding abutments 16 under compression and the yielding action of these abutments and in the supporting structures themselves will keep the free end of the brace 7 securely interlocked with the cleat 17. The 65 brace 7, of course, firmly supports the rear legs 5 in upright or approximately vertical positions. When the supporting structure is to be folded up against the board, it is only necessary to spring the free end of the brace 75 out of engagement with the cleat 17 and then to press the leg structure into flat arrangement against the bottom of the board. The ironing table thus folded will occupy 80 very little space. The bifurcation and spreading of the leg 6 and the brace arm 7 gives the board-supporting structure very considerable lateral rigidity as well as a rigid 85 vertical support for the board.

What I claim is:—

An ironing table comprising an ironing board, rear legs and an oblique leg pivoted to the rear end of said board, means to cause said oblique leg to have a limited downward movement in respect to said board, and a brace pivotally connected to the rear legs and having detachable interlocking engagement with the front end of said board, said brace having a stop member intermediate of its ends engageable with the top of said oblique leg and slidably therealong to maintain the board in working position under compressive forces applied to the brace.

15 In testimony whereof I affix my signature.

JOHN E. KALGREN.
